US00D587234S

(12) **United States Design Patent**
Kim et al.

(10) **Patent No.:** **US D587,234 S**
(b4) **Date of Patent:** **** Feb. 24, 2009**

(54) **PORTABLE PHONE**

(75) Inventors: **Young-Sae Kim**, Palo Alto, CA (US);
Ji-Eun Lee, Seoul (KR); **Young-Ju Yeo**, Seoul (KR); **Chang-Soo Lee**, Incheon-Si (KR)

(73) Assignee: **Samsung Electronics Co., Ltd.**, Suwon-Si (KR)

(**) Term: **14 Years**

(21) Appl. No.: **29/300,730**

(22) Filed: **Apr. 30, 2008**

(51) **LOC (9) Cl.** **14-03**

(52) **U.S. Cl.** **D14/138 AD**

(58) **Field of Classification Search** **D14/137, D14/138 R, 138 AA, 138 AB, 138 AC, 138 AD, D14/138 C, 138 G, 147, 191, 218, 247-248, D14/341-347, 455, 496; D10/65, 78, 104; D13/168; D18/7; 455/556.1, 566, 575.1, 455/575.3; 345/169**

See application file for complete search history.
